UNITED STATES PATENT OFFICE

RICHARD A. BATES, OF EAST CHICAGO, INDIANA, ASSIGNOR TO BATES EXPANDED STEEL TRUSS COMPANY, OF EAST CHICAGO, INDIANA, A CORPORATION OF DELAWARE

JOIST AND THE MANUFACTURE THEREOF

Application filed May 7, 1928. Serial No. 275,662.

The invention relates to the manufacture of expanded metal joists or beams and more particularly to the manufacture of those joists which are formed of an integrally flanged metallic structural element such for example as an I-beam, and have the web-portion between the flanges slit and expanded to form diagonal trussing consisting of compression and tension members.

10 One object of the present invention is to provide a joist or beam of this character in which the ends are not slit or expanded so that they are of maximum strength and the end portions of the bottom flange operate as integral bearing plates whereby the joist is held in its operative position against transverse rocking movement, and in which the lower member consisting of the central or intermediate part of the bottom flange and 15 the adjoining web-portion is in suspension 20 and is independent of the bearing plates or the ends of the joist.

Another object of the invention is to provide a method of manufacturing joists or 25 beams of the aforementioned construction by which the joists may be manufactured at a comparatively low cost and with a minimum number of operations.

A further object of the invention is to provide a joist or structural supporting element 30 which is of new and improved construction and may be readily and economically fabricated and utilized for building and other purposes.

35 In addition the invention contemplates as one of its objects to improve the joist construction and manufacturing method disclosed in an application of Albert J. Bates, Jr., for Letters Patent of the United States for improvements in "metal joists and the manufacture thereof," filed October 8, 1927, and serially numbered 224,802.

Other objects will be manifest from a reading of the detailed description which follows.

40 The invention consists in the several novel features hereinafter set forth and more particularly defined by the claims at the conclusion hereof.

45 In the drawing which accompanies and forms a part of this specification or descrip-

tion and in which like characters of reference denote corresponding parts throughout the several views:

Figure 1 is a side elevation of an I-beam from which the joist or supporting beam 55 is formed;

Figure 2 is a similar view illustrating in detail the manner of slitting the beam before it is expanded;

Figure 3 is a side elevation of the beam 60 after it has been expanded;

Figure 4 is a side elevation of the finished joist showing the same in its operative position;

Figure 5 is a section taken on the line 65 5—5 of Figure 4;

Figure 6 is a section taken on the line 6—6 of Figure 4; and

Figure 7 is a section taken on line 7—7 of 70 Figure 4.

The invention is exemplified in a joist, beam, or structural supporting element comprising a longitudinal upper member which consists of a vertical web a^1 and a horizontal flange a^2 projecting laterally from both sides 75 thereof and forming the top of the joist; a lower longitudinal member which consists of a vertical web a^3 and a horizontal flange a^4 projecting laterally from both sides thereof and forming the bottom of the joist; a series of substantially parallel diagonal truss members a^5 which extend between the vertical webs a^1 and a^3 of the upper and lower members; and a series of oppositely extending diagonal truss members a^6 which also 80 extend between the webs of the upper and lower members. The truss members a^5 and a^6 are medially united and together form tension and compression members. All of the 85 parts or members which together form the joist are integral and are formed of an I-beam or bar A, such, for example, as the one shown in Figure 1. The upper and lower flanges of this bar correspond to the flanges a^2 and a^4 of the joist.

In the fabrication or manufacture of the joist, the web between the flanges is first sheared to form an upper series of longitudinally aligned slits a^7 with bonds or intact portions a^8 between them, a lower series of 100

longitudinally aligned slits a^9 with bonds a^{10} between them, and a central or intermediate series of slits a^{11} with bonds a^{12} between them. The slits of the lower series are parallel with the slits a^7 of the upper series and are coextensive therewith. The slits of the intermediate series are equal in length to the slits a^7 and a^9 and are staggered relatively thereto so the bonds a^{12} are positioned midway between the bonds a^8 and a^{10} . The portions of the web between the slits form strands which, when expanded or spread apart as hereinafter described constitute the tension and compression truss members a^5 and a^6 .

The lower series of slits a^9 as well as the upper and intermediate series terminates some distance inwardly of the ends of the beam so as to form supporting portions a^{13} . These portions are left uncut and as a result are of a height equal to the entire width of the beam A, that is, they are equal to the aggregate height of the web a^1 , the strands between the slits a^7 and a^9 , the web a^3 and the flanges a^2 and a^4 . The end portions of the flange a^4 which underlie the portions a^{13} form bearing plates a^{14} at the ends of the joist whereby the joist may be supported in its operative position upon a suitable supporting structure, such, for example, as the I-beams B shown in Figure 4. In operation or use, the plates a^{14} serve to hold the joist against transverse rocking movement and prevent the joist from cutting into the supporting structure which sometimes is of brick-work. A characteristic of forming the ends of the joist in this manner is that they are of maximum strength due to the fact that they are uncut and no additional or non-integral reinforcement is necessary. Additionally the bearing plates a^{14} are formed as an integral part of the portions a^{13} with the result that the use of separate members and the incident welding or fastening operation are dispensed with.

The end slits of the intermediate series are extended as at a^{15} toward the beam-ends. The extended parts of these slits terminate a short distance inwardly of the end slits of the lower series. The upper slits a^7 are omitted from the portions of the beam disposed inwardly of the portions a^{13} above said end slits of the lower series so as to eliminate compression or downwardly and outwardly extending truss members, adjacent the beam-ends and so that the upper member of the joist is additionally reinforced adjacent the ends thereof. By omitting these slits, portions a^{16} are provided between the end portions a^{13} and the second diagonal or truss members of the joist. These portions are of a height equal to the aggregate height of the vertical web a^1 and the strands between the slits a^7 and a^{11} and operate to reinforce the joist at the places where most needed. A

characteristic of terminating or omitting the slits a^7 at the ends of the beam as set forth and shown is that there are only tension truss members adjacent the beam-ends and the metal which would otherwise form downwardly and outwardly extending compression members adjacent the ends of the joist, as in the criss-cross trussing of the central portion, is utilized to provide additional reinforcement against longitudinal tending movement.

The end slits of the lower series terminate inwardly of the end edges of the beam a sufficient distance to give the supporting portions a^{13} the desired or necessary length. So that the ends of the lower member of the joist will be in suspension after the expanding or stretching operation, the beam is sheared transversely to form slits a^{17} which extend upwardly from the bottom flange to the outer terminating points of the end slits of the lower series. These slits a^{17} extend completely through the portions which form the web a^3 and flange a^4 of the lower member of the joist, with the result that the ends of said lower member are separate from the supporting portions a^{13} and, after the expanding operation, are in suspension. A characteristic of shearing the beam in this manner instead of cutting and extending the end slits of the lower series to intersect the end edges of the beam as shown and described in the aforementioned application of Albert J. Bates, Jr., is that the metal which would ordinarily have to be sheared away so that the ends of the lower member will not abut against or interfere with the supports or I-beams B, remains in place and is utilized to form the bearing plates a^{14} . Furthermore, the ends of the lower member are properly spaced with respect to the portions a^{13} without additional shearing or cutting. An additional characteristic of slitting the beam in the manner set forth is that no additional operation is necessary after the expanding operation, as the joist is complete and ready for use. By having the end slits of the lower series extend outwardly or beyond the end slits of the intermediate series the end compression members are connected to the portions a^{13} and a^{16} by sizable or pronounced parts a^{20} .

After the beam A has been slit as described, it is heated and the upper and lower flanges a^2 and a^4 are spread apart in parallelism by suitable expanding mechanism into the position shown in Figure 3. This expanding operation stretches and deflects the strands between and formed by the slits a^7 , a^8 and a^9 into the diagonal truss members a^5 and a^6 , leaving their ends joined to the web of the upper and lower members and their medial portions joined together. This forms a series of diamond shaped openings in the web and permits the extent of expansion

sion necessary to form a joist of any desired height. The metal at the ends of the beam which is included in the portions a^{18} being uncut is left in its original form. Since the 5 ends of the lower member are severed from these portions by the slits a^{17} it is manifest that they will not be deflected similarly to the end tension members but will be expanded in parallelism with the intermediate part of the lower member. The slits a^7 are spaced from the flange a^2 a greater distance than the slits a^9 are spaced from the flange a^4 to give greater strength to the upper member.

Struts a^{18} are placed between the upper 15 and lower longitudinal members of the joist in the end openings to act as vertical compression members between said longitudinal members. These struts have their upper ends welded as at a^{19} to the inner ends of the 20 portions a^{16} and their lower ends welded to the end bonds a^{10} . By positioning the struts a^{18} as set forth, that is, a suitable distance from the ends of the beam downward stresses are transmitted directly from the 25 upper member to the lower member at the most suitable points or locations.

The joist or structural supporting element disclosed herein is of an improved character because the ends of the I-beam from 30 which it is formed remain uncut and therefore are of maximum height and strength and the ends of the lower member of the joist are in suspension and properly spaced with respect to the supported end portions. The 35 joist may be readily manufactured and is complete and ready for immediate use after the expanding operation, as no additional shearing and no welding is necessary after said expanding operation.

The slitting of the beam A may be advantageously done in a machine of the character 40 set forth in an application filed November 5, 1926, by the aforesaid Albert J. Bates, Jr., and serially numbered 141,702. The expanding may be done in a machine of the 45 type set forth in Letters Patent of the United States No. 1,260,857, dated March 26, 1918.

The invention is not to be restricted to the 50 specific details set forth, since these may be modified within the scope of the appended claims, without departing from the spirit and scope of the invention.

Having thus described the invention, what I claim as new and desire to secure by Letters 55 Patent, is:

1. A joist or supporting beam comprising an upper longitudinally extending member 60 embodying a web-portion, the ends of said web-portion being enlarged downwardly and having integral laterally extending flanges at the lower marginal parts thereof, a lower longitudinally extending member also embodying a web-portion, and diagonal trussing 65 between and integral with the members and at the central part thereof, the ends of

said lower member being disconnected from and terminating inwardly of the enlarged flanged ends of the upper member.

2. A joist or supporting beam comprising an upper longitudinally extending member 70 embodying a web-portion, the ends of said web-portion being enlarged downwardly and having integral laterally extending flanges at the lower marginal parts thereof, a substantially straight lower member parallel with the upper member and embodying a web-portion and a bottom laterally extending flange, and oppositely extending medially united diagonal truss members between and integral with the central parts of the web-portions of said members, the ends of the lower member being in suspension and terminating inwardly of the enlarged flanged ends of the upper member.

3. An expanded metal joist formed of a 85 beam having a vertical web and an integral flange at the lower margin of the web, and comprising an upper longitudinal member including the upper central part of the web and the complete and flanged end parts of the beam, a lower longitudinal member including the lower central part of the web and the contiguous and medial portion of the flange, and diagonal truss members extending between the web portions of the longitudinal members, said truss members being formed of the intermediate central part of the web, the end portions of the flange at the 90 ends of the upper member forming bearing plates for the joist.

4. An expanded metal joist formed of an I-beam and comprising an upper longitudinal member including the complete and unchanged ends of the beam, the top flange and the upper part of the web, a lower longitudinal member including the lower central portion of the web and the contiguous and medial portion of the lower flange, and diagonal truss members extending between the longitudinal members and formed of the intermediate central part of the web, the ends 105 of the lower member being in suspension and terminating inwardly of the double flanged ends of the upper member.

5. That improvement in the manufacture 110 of expanded metal joists which consists in slitting the medial portion of a flanged beam to form an upper and a lower longitudinal member and a series of expansible strands between and bonded to said members, and cutting the beam transversely adjacent the ends thereof so as to cause the entire flanged end parts of the beam to be associated with the ends of the upper member and also cause the ends of the lower member to terminate inwardly of and to be disconnected with respect to the said flanged end parts of the upper member; and then expanding the beam to space apart the longitudinal members and 120 form of the strands diagonal truss members.

6. That improvement in the manufacture of expanded metal joists which consists in slitting the medial portion of a flanged beam to form an upper and a lower longitudinal member and two intermediate and side by side series of expansible strands with bonds between themselves and said members, and cutting the beam transversely adjacent the ends thereof to cause the entire flanged end parts of the beam to be associated with the ends of the upper member and also cause the ends of the lower member to terminate inwardly of and to be disconnected with respect to the said flanged end parts of the upper member; and then expanding the beam to space the members in parallelism and form of the strands oppositely extending and centrally joined diagonal truss members.
7. That improvement in the manufacture of expanded metal joists which consists first in slitting the medial portion of a flanged beam on a plurality of longitudinal lines to form an upper and a lower longitudinal member and a series of strands between and bonded to said members, cutting the beam transversely near the ends thereof to intersect the outer ends of the end slits of the lower line so as to cause the entire flanged end parts of the beam to be associated with the ends of the upper member and also cause the ends of the lower member to terminate inwardly of and to be disconnected with respect to the said flanged end parts of the upper member; and then expanding the beam to space the members apart and form of the strands diagonal truss members.
8. That improvement in the manufacture of expanded metal joists which consists first in slitting the medial portion of an I-beam on three longitudinal lines to form an upper and a lower longitudinal member and two intermediate and side by side series of expansible strands with bonds between themselves and said members, and cutting the beam transversely through the lower flange up to the outer ends of the end slits of the lower line so as to cause the entire flanged end parts of the beam to be associated with the ends of the upper member and also cause the ends of the lower member to terminate inwardly of and to be disconnected with respect to the said flanged end parts of the upper member; and then expanding the beam to space in parallelism the members and form of the strands oppositely extending and centrally joined diagonal truss members.

Signed at East Chicago, Indiana, this 30th day of April, 1928.

RICHARD A. BATES.
